UNITED STATES PATENT OFFICE.

LEWIS AUGUSTUS ASPINWALL, OF JACKSON, MICHIGAN, ASSIGNOR TO
ASPINWALL MANUFACTURING COMPANY, OF JACKSON, MICHIGAN,
A CORPORATION OF MICHIGAN.

POTATO-DIGGER.

SPECIFICATION forming part of Letters Patent No. 709,659, dated September 23, 1902.

Application filed February 3, 1902. Serial No. 92,238. (No model.)

To all whom it may concern:

Be it known that I, LEWIS AUGUSTUS ASPINWALL, a citizen of the United States, residing at Jackson, in the county of Jackson and 5 State of Michigan, have invented an Improvement in Potato-Diggers, of which the following is a specification.

My present invention is designed as an improvement upon devices heretofore employed 10 by me with the object of simplifying the construction, strengthening the parts, making more positive and efficient the various movements, and also imparting to the second movement or separator a feature adapted to be 15 adjusted for controlling the movement of the swinging separator-forks according to the character of the earth that the machine is acting upon.

In my present invention the frames are 20 strongly made and firmly connected and are of such form, together with the bearings, that all the parts are carried by and swing upon the main axle, and the moving parts are to a large extent covered and protected from contact with earth and vines that might act to 25 clog the same or impede their movements, and parts of the first movement or pulverizer and the second movement or separator are adapted to swing into more or less of a gravity position and to be momentarily carried in 30 such position, so as to lessen the power necessary to operate the machine and at the same time perform useful functions. The pulverizer-arms are of bent form and pass through 35 openings provided between parts secured to and rotating with the power-shaft of the said device, and said arms are provided with crank-arms and rollers bearing in their operative position upon a cam, the cam being 40 so formed as to release the arms and allow them to drop by gravity when not in an operative position. In the second movement or separator there are series of swinging forks pivoted in a revoluble head, the arbors of the 45 forks turning in tangential sleeves of the revoluble head, a disk cam being provided and the arbors of the forks having cranks and rollers, the rollers bearing upon said cam-disk for part of their rotation and running off

the cam and hanging free in the other part of 50 their movement, said forks being held while the earth, potatoes, and tops are delivered thereon from the arms of the pulverizer, so that the earth falls through the tines of the forks, and the potatoes and vines remain 55 thereon and are delivered onto the ground as soon as the forks turn when released from the cam, and the cam-disk is adjustable so as to prolong the time when the earth, potatoes, and tops remain thereon, the same being ad- 60 vantageous in working in wet earth in contradistinction to working in dry or loamy soil. All of these features are hereinafter more particularly set forth.

In the drawings, Figure 1 is a side elevation 65 representing my improvement, one of the wheels being removed for clearness of illustration. Fig. 2 is a plan and partial section representing the essential features of my invention, the same being taken upon a line below the shaft and sleeve and without the 70 wheels. Fig. 3 is an end elevation of the cam employed with the first movement or pulverizer. Fig. 4 is an elevation and partial cross-section illustrating my improvements, said Fig. 4 being without the first movement, the plow or grating. Fig. 5 is a 75 sectional plan through the frame and above the swinging forks of the second movement or separator. Fig. 6 is a side elevation of 80 the cam employed in connection with the second movement, said cam also appearing in Figs. 1, 4, and 5. Fig. 7 is a cross-section through part of the revoluble head, showing a crank-arm and roller and a stop for limiting the movement of the same.

a a' represent the wheels of the potato-digger; *b*, the axle; *c*, a sleeve surrounding a portion of said axle, and *c'* flanges upon opposite sides of said sleeve and occupying a 90 substantially horizontal or slightly-inclined position. Either or both of the wheels *a a'* are employed for imparting power to drive the mechanism with the movement of the digger, the devices for accomplishing the same 95 being well known in the art and requiring no further description and no illustration. The said sleeve *c* and side flanges *c'*, supported by

the axle *b*, carry all the framework, the bearings, and the parts of the different movements from the axle, and all of said parts swing upon the axle.

5 The dishing frame *d* is provided with a flange and by bolts is secured to the side flanges *c*', and said frame *d* is provided with openings for the shafts of the respective movements. A sleeve *e*, forming a bearing 10 for the shaft of the first movement, is provided with a flange 2, coming adjacent to one of the openings in the frame *d*, and upon the other end of the sleeve *e* is a cam *e*'. Said sleeve *e* is also provided with side flanges 3, 15 one of which is secured to a lug on the frame *d* and the other to a flange 4 at one side of a sleeve *f*, which forms a bearing for the shaft of the second movement. This sleeve *f* is provided with a flange 5, by which the same 20 is secured to the dishing frame *d*, and a part at one end of said sleeve passes through an opening in said frame *d*.

I provide a hollow casing *g*, having side flanges *g*', resting upon and bolted to the 25 flange 4 of the sleeve *f*, and which receives the opposite end of the sleeve *f* and which also receives an axis 6, fixed thereto by a bolt 7, said axis being slightly inclined from a vertical plane, and a bracket 8, secured to one 30 of the side flanges *c*', is also connected by the same bolt 7 to the hollow casing *g*, thereby further supporting said casing and said axis 6 from the side flanges *c* and causing the parts *f* and *g* to coact in a supporting relation 35 the one to the other. A malleable cast frame *h*, secured to the dishing frame *d*, forms a forward prolongation of said frame and supports the plow *i*, a grating-frame *k*, and a grating *k*', all of which parts are connected 40 to the said frame *h*.

A ratchet 9 and gear 10 are connected and are mounted upon the axle *b*, and they are preferably connected to the axle *b*, it being a fact in this art that the wheels are usually 45 loose upon the axle and are provided with one or more pawls at one or both sides of the machine, engaging one or more such ratchets for the purpose of communicating the power of the wheels to the axle in operating the 50 mechanism as the machine is drawn over the ground, the wheels directly communicating the power. I provide a pinion 11, meshing with the gear 10, and a bevel-gear 12, both of which are upon the shaft 17, which passes 55 through the bearing-sleeve *f*.

A pinion 13 is upon one end of the shaft 14, which passes through the sleeve *e*, and the pinion 13 is in mesh with the bevel-gear 12, power being communicated from the gear 10 through the pinion 11 and gears 12 and 13 to the said shaft 14. The pinion 13 and shaft 14 form part of the first movement or pulverizer, and upon the forward end of the shaft 14 I provide the pulverizer device, which essentially comprises a dishing disk *l* and plate *l*', secured together and substantially in one piece and provided with radially-spaced-

apart openings, the same being secured to the forward end of said shaft 14, so as to turn therewith.

The pulverizer-arms 15 are bent, with parts at approximately right angles to one another. The inner ends of said arms pass through the radial openings between the parts *l* and *l*', and the inner ends of said arms are provided with crank-arms carrying rollers, and the rollers bear upon the surface of the cam *e*'. The rollers and cranks follow the crank-arms with the rotary movement imparted to the pulverizer, and where the rollers bear upon the cam they hold the pulverizer-arms in position. This cam *e*' has operative and non-operative surfaces, and when the rollers run off the operative surface they permit the pulverizer-arms at their outer ends 80 to drop by gravity and occupy a hanging position. In the second movement a bevel-gear 18 is secured to one end of the shaft 17 and is within the hollow casing *g*, and I provide a bevel-gear 19, meshing therewith and 85 loosely surrounding the axis 6, and this bevel-gear 19 is secured to a revoluble head *m*, and through said head the axis 6 passes, there being an intermediate ring-frame 20 secured to the flange of the sleeve *f* and coming below the 90 lower edge of the hollow casing *g*, so as to completely inclose the bevel-gears 18 and 19 and keep out dust and dirt. The revoluble head *m* is of peculiar form, as will be seen by 95 reference to Figs. 4 and 5, the same being provided with tangent-sleeves *m*', projecting from the main portion of the said head. This head is open underneath, provided with a sleeve, and it and the bevel-gear 19, connected therewith, are held in position and in their 100 relation to the ring-frame 20 and casing *g* by the disk cam *o*, which is upon the axis 6 and is securely held thereto in the desired position by a bolt.

The swinging forks *n* of the separator device are shown in a series of eight with four tines each, and they are made with arbors *n*', there being by preference collars upon said arbors coming against the outer ends of said sleeves, and upon the inner ends of said arbors I provide cranks 21, carrying rollers 22 and preferably made with projections 23 on the heel of the cranks. From Figs. 1, 4, 5, and 6 the form of the cam-disk *o* will be apparent, and the rollers 22 bear upon part of the surface of said cam-disk—that is, the surface substantially flat and nearest in the plane of the arbors *n*'—the said rollers running off the inclined portion of said cam-disk at one side and running on the inclined portion at 125 the other side with their rotary movement. These surfaces are flat and are at an obtuse angle to one another.

From Figs. 4 and 5 the position of the swinging forks will be especially apparent, there 130 being four of the series where the rollers are bearing upon the flat portion of the cam adjacent to the plane of the arbors, and in which position the forks are held in their operative

position for work. Two of the series of forks are shown with their rollers out of contact with the cam and with the forks turned down and substantially hanging by gravity. One 5 of the said series of forks is shown as running off the cam and another as running on, in both of which positions the inclination of the forks is shown as different from the working position or the hanging position, the one going 10 to the hanging position and the other going to the working position. The projection 23 on the heel of the cranks 21 comes against the flange of the head *m*, so as to limit the extent of downward or hanging movement of 15 the forks of the series and also to lessen the extent to which the cranks and rollers as acting upon the cam-disk have to lift the swinging forks when returning them to their working position.

20 The operation of the various parts is substantially as follows: As the digger is drawn along with the plow in the earth the earth, with the potatoes and tops in the row, passes up the plow onto the grating *k'*. The forward 25 movement of the machine by the gears, bevel-wheels, and shafts, hereinbefore described, actuates the first movement or pulverizer and also the second movement or separator, and the pulverizer-arms 15 move around with the 30 disk *l* and plate *l'*. In the direction of rotation the resistance offered by the material presses against the bent pulverizer-arms and brings the crank ends and rollers against the cam. This arrests the movement of said arms 35 and applies the power through the medium of the parts described, so that said pulverizer-arms move the earth, potatoes, and tops not only along the curved surface of the grating, but throw and deliver the same over upon the 40 separator-forks. As the pulverizer-arms rise above the level of the grating after performing their work the rollers of the crank-arms run off the cam and the arms drop by gravity, discharging the load or material, after which they 45 again come around into the operative position, so that during part of the movement they substantially hang free and move with the said disk and plate. As the earth and potatoes, with the tops, are delivered upon the swinging 50 forks of the separator the earth is comparatively loose and falls through between the tines of the forks, leaving the potatoes and the tops thereon, and if the earth does not at once fall away there is an appreciable 55 period in the rotation of the separator in which the earth will have time to disintegrate and fall away from the forks. The separator-forks are held in the desired position by the cranks and rollers on their inner ends bearing 60 against the surface of the disk cam *o*, and they are held in operative position by the disk cam while their rollers are running upon the substantially horizontal surface thereof. The operative position of the swinging forks 65 is maintained for substantially a half-rotation of the separator, and toward the rear of the machine the rollers run upon the incline

of the disk cam, permitting the forks to swing by gravity and gradually deliver the potatoes and tops upon the surface of the ground. 70 There is a part of this rotary movement when the rollers of the forks are free from the surface of the disk cam and in which the forks hang from the revoluble head *m* by gravity, requiring no power or force for their operation. 75 They thereafter assume the desired operative position as the rollers 22 run up the inclined surface of the disk cam onto the substantially horizontal portion. The disk cam *o* is held in position by a set-screw bearing 80 against the axis 6, and I have shown in Figs. 1 and 4 and prefer to provide a pin 24, passing through the axis 6 beneath the hub of the disk cam, so as to prevent the cam dropping upon the axis, but permit the same to 85 be turned to adjust the operative position of the swinging forks.

I claim as my invention—

1. In a potato-digger, the combination with a plow and grating, of a pulverizer device including bent swinging arms and means for controlling the movements and operative position of said arms when the same are in operative position, and which devices permit the arms out of position to be free, and 90 a separator device including a series of swinging forks, and devices substantially as shown and described for supporting said forks in their operative position but which allow said forks to deliver the potatoes and tops and to 100 hang in a position of gravity during part of their movement, substantially as set forth.

2. In a potato-digger, the combination with the plow and grating, of a pulverizer device comprising a series of bent pivoted arms, a 105 shaft and devices connected thereto and to which said arms are pivotally connected, cranks and rollers on the inner ends of said arms and a cam acting upon said rollers for controlling the movements of said arms and 110 permitting said arms during part of their movement to hang free, substantially as set forth.

3. In a potato-digger, the combination with the plow and grating, of a pulverizer device 115 comprising a series of bent pivoted arms, a shaft and devices connected thereto and to which said arms are pivotally connected, cranks and rollers on the inner ends of said arms, and a cam acting upon said rollers for 120 controlling the movements of said arms and permitting said arms during part of their movements to hang free, a sleeve forming part of the frame of the machine and secured thereto and on one end of which said cam is 125 formed, and gears connecting the opposite end of said shaft to the axle of the machine for effecting the rotary movement of the pulverizer device, substantially as set forth.

4. In a potato-digger, the combination with 130 the plow and grating, of a bearing-sleeve *e* forming part of and secured to the frame of the machine and having a cam *e'* at one end, a shaft 14 passing through said sleeve, a disk

- l* and plate *l'* secured together and connected upon one end of the said shaft, a pinion 13 upon the opposite end of said shaft, pulverizer-arms 15 of bent form journaled between 5 the disk *l* and plate *l'*, crank-arms 16 on the ends of said pulverizer-arms and rollers carried thereon and for part of the rotary movement of said pulverizer device bearing upon the surface of the cam *e'*, substantially as 10 and for the purposes set forth.
5. In a potato-digger, the combination with the plow and grating, of a bearing-sleeve *e* forming part of and secured to the frame of the machine and having a cam *e'* at one end, 15 a shaft 14 passing through said sleeve, a disk *l* and plate *l'* secured together and connected upon one end of the said shaft, a pinion 13 upon the opposite end of said shaft, pulverizer-arms 15 of bent form journaled between 20 the disk *l* and plate *l'*, crank-arms 16 on the ends of said pulverizer-arms and rollers carried thereon and for part of the rotary movement of said pulverizer device bearing upon the surface of the cam *e'*, a bevel-gear 12, a 25 pinion 11 connected therewith, a shaft and bearings therefor, a gear 10 and ratchet 9 connected together upon the main shaft of the machine with the gear 10 meshing with the pinion 11 for communicating the power 30 and movement of the axle to the pulverizer device, substantially as set forth.
6. In a potato-digger, the combination with the wheels, the axle and a sleeve *c* having side flanges *c'* surrounding said axle, of a 35 dishing frame *d* secured to said flanges *c'*, a frame *h* secured to the frame *d*, a grating-frame *k* secured to the frame *h* and the grating and plow secured respectively to the frame *h* and the grating-frame *k*, substantially 40 as set forth.
7. In a potato-digger, the combination with the wheels, the axle, a sleeve surrounding the axle and side flanges formed with the sleeve, of a dishing frame *d* secured to the 45 said side flanges, a sleeve *f* passing through an opening in the frame *d* and having a flange 5 by which the same is secured to said frame *d*, a lug also formed with the frame *d*, a sleeve *e* and integral cam *e'*, said sleeve passing 50 through a second opening in the frame *d*, and a flange 2 formed with the sleeve *e* and coming against the surface of the frame *d*, flanges 3 formed with the sleeve *e*, and bolts for connecting the said flanges and sleeve to the 55 flange 4 and the lug of the frame *d*, substantially as set forth.
8. In a potato-digger, the combination with the wheels, the axle, a sleeve surrounding the axle and side flanges formed with the sleeve, 60 of a dishing frame *d* secured to the said side flanges, a sleeve *f* passing through an opening in the frame *d* and having a flange 5 by which the same is secured to said frame, a flange 4 formed with the sleeve *f*, a hollow 65 casing *g*, an axis 6 within the same, a bracket 8 secured to the side flanges of the axle-sleeve, and a bolt 7 passing through said bracket and

through the hollow casing and axis for connecting the parts, and a ring-frame 20 secured to the sleeve *f* and coming below the hollow 70 casing *g*, substantially as set forth.

9. In a potato-digger, the combination with a fixed axis and means for supporting and inclosing the same, of a separator device comprising a revoluble head *m* and connected bevel-gear 19 surrounding the said axis, a series of swinging forks *n* pivotally mounted in said 75 revoluble head, cranks and rollers on their inner ends, and an adjustable cam-disk secured to the said fixed axis below the plane of the 80 swinging forks, substantially as and for the purposes set forth.

10. In a potato-digger, the combination with a fixed axis and means for supporting and inclosing the same, of a separator device comprising a revoluble head *m* and connected bevel-gear 19 surrounding the said axis, a series of swinging forks *n* pivotally mounted in said 85 revoluble head, cranks and rollers on their inner ends, and an adjustable cam-disk 90 secured to the said fixed axis below the plane of the swinging forks, a shaft 17, a bevel-gear 18 on one end thereof meshing with the aforesaid bevel-gear 19, a pinion 11 on the shaft 17, a gear 10 and connected ratchet 9 on the 95 axle of the machine by which power and rotation are communicated to the device of the separator, substantially as set forth.

11. In a potato-digger, a separator device comprising a revoluble head *m* having tangent sleeves *m'* projecting from the main portion of said head, a sleeve at the center of said head the same being open underneath, a bevel-gear connected to said head, a fixed axle-support passing through the bevel-gear and 100 sleeve of the head, a series of swinging forks each comprising a multiplicity of tines, an arbor passing through a tangent sleeve, a crank on the other end of the arbor and within the 105 said head, and a roller on the crank, and a 110 cam-disk adjustably mounted on the central supporting-axis and upon which the said rollers bear, substantially as set forth.

12. In a potato-digger, a separator device comprising a revoluble head *m* having tangent sleeves *m'* projecting from the main portion of said head, a sleeve at the center of said head, the same being open underneath, a bevel-gear connected to said head, a fixed axle-support passing through the bevel-gear and 115 sleeve of the head, a series of swinging forks each comprising a multiplicity of tines, an arbor passing through a tangent sleeve, a crank on the other end of the arbor and within said 120 head, and a roller on the crank, and a cam-disk *o* adjustably secured upon the central supporting-axis and having two substantially 125 flat faces at approximately obtuse angles to one another, the higher surface of said cam being the operative surface thereof and acting to hold the series of forks in their operative position, and the inclined surface permitting the forks to swing upon their arbors, 130 substantially as set forth.

13. In a potato-digger, a separator device comprising a revoluble head *m* having tangent sleeves *m'* projecting from the main portion of said head, a sleeve at the center of said head, the same being open underneath, a bevel-gear connected to said head, a fixed axial support passing through the bevel-gear and sleeve of the head, a series of swinging forks each comprising a multiplicity of tines, an arbor passing through a tangent sleeve, a crank on the other end of the arbor and within said head, and a roller on the crank, and a cam-disk adjustably mounted on the central sup-
- porting-axis and upon which the said rollers bear, and projections 23 upon the cranks of 15 the swinging forks and bearing against the revoluble head for limiting the downward or gravity movements of said swinging forks, substantially as set forth.

Signed by me this 18th day of December, 1901.

LEWIS AUGUSTUS ASPINWALL.
